REEL ADAPTER FOR A MAGNETIC TAPE RECORDER

Fred Burhorn Kirk, Denver, Colo., assignor to Roberts
Electronics, Inc., Los Angeles, Calif., a corporation of
California

Filed Apr. 6, 1962, Ser. No. 69,611

Term of patent 14 years

(Cl. D26—14)

FIG. 1 is a front, top and side perspective view of a reel adapter for a magnetic tape recorder, showing my new design.

FIG. 2 is a top plan view thereof.

FIG. 3 is a rear elevation thereof.

FIG. 4 is a bottom plan view thereof.

FIG. 5 is a side elevation thereof, the opposite side being substantially a mirror image thereof.

I claim:

The ornamental design for a reel adapter for a magnetic tape recorder, as shown and described.
